TOOL POST

Peter Lustrik, Cleveland, Ohio

Application February 15, 1943, Serial No. 475,919

1 Claim. (Cl. 82—37)

This invention relates broadly to machine tools and more specifically to improvements in tool posts therefor.

The objects of the invention reside in the provision of a supporting structure which is designed to accommodate the securement and adjustments of the tool through manipulation of a single locking element, a structure which will facilitate the support of the tool in closer proximity to the chuck than possible in the slotted tool post of conventional design; a structure which will accommodate the support of tool bit holders or tools of various widths, a clamping structure which can be readily adapted for use in machines having different T-slot specifications and a clamping foot construction which is designed to avoid injury to the compound rest, table or platen of the machine.

Other objects and advantages more or less ancillary to the foregoing and the manner in which all the various objects are realized will appear in the following description, which considered in connection with the accompanying drawing, sets forth the preferred embodiment of the invention.

Referring to the drawing:

Fig. 1 is a plan view of the improved tool post including a fragmentary portion of one of the members of a compound rest;

Fig. 2 is a side elevational view of the tool post illustrated in Fig. 1;

Fig. 3 is a vertical sectional view thereof, the section being taken on a plane indicated by the line 3—3 in Fig. 2; and

Fig. 4 is an end elevational view of the tool post.

Referring first to Fig. 3, the tool post comprises a column 10 formed with an integral rectangular base or foot 11 machined for sliding engagement within the T-slot of a compound rest 12 of a lathe or table of a similar machine. The free end of the column is drilled and tapped for the reception of a cap screw 13 formed with an enlarged head constituting a shoulder to arrest the upward movement of a sleeve 14 telescopically engaged with the column 10. The sleeve is provided with an overhanging boss 15 drilled and tapped to receive a set screw 16 disposed for engagement with the shank of a cutting tool or a tool bit holder 17 of conventional form. The cutting tool is supported upon a block 18 having an arcuate face therein which is adapted for rocking engagement within a curve seat of complementary configuration in a plate 19. The plate, as shown in Fig. 3, is bored for telescopic engagement with the column 10 and is

preferably of rectangular form in order to provide a substantial bearing surface for engagement with the face of the machine table or compound rest. The plate 19 is provided with a dowel pin 20 engageable within an opening 21 in the sleeve 10 to prevent independent rotation of the sleeve and plate during angular adjustments of the tool.

In operation after the tool is seated upon the block 18 and suitably elevated relative to the work through the medium of the block 18 the set screw 16 may be tightened, the clamping action being obtained by the tensile effort upon the foot 11, the upward thrust of the sleeve 14 against the head of the cap screw 13 and the compressive effort between the tool 17, tool block 18 and plate 19.

It will be noted that the rectangular foot 11 will provide substantial bearing against the faces of the flanges defining the T-slot, that the lineal side walls of the foot will prevent rotation of the column and that the localized wear customary in tool posts having circular bases is thus avoided. It will be further noted that the structure embodying the present invention is formed, as shown in Fig. 4, to permit the column to be adjusted in close proximity with the end of the compound rest, in order to facilitate the adjustments of the tool relatively close to the chuck or face plate 20 and the support of the tool while so adjusted with the clamping screw adjacent the cutting edge thereof. It will be recognized that the open sided tool post structure facilitates the use of tools or tool holders of various widths and also accommodate the ready insertion, removal or adjustment of the tool through manipulation of the single set screw 16. When it is desired or necessary to use the improved tool post in machines having a T-slot of different size a new column 21 may be readily substituted in the assembly, the other elements of the organization being interchangeable therewith. In the event the tooling requirements necessitate the elevation of the cutter beyond the limits provided by the height of the shoulder formed by the screw 13, a new screw formed with a shank of suitable length and a flanged head portion may be used in place of the screw illustrated herein.

Although the foregoing description is necessarily of a detailed character, in order that the invention may be completely set forth, it is to be understood that the specific terminology is not intended to be restrictive or confining, and that various rearrangements of parts and modifications of detail may be resorted to without de-

parting from the scope or spirit of the invention as herein claimed.

I claim:

A tool post comprising a column, a rectangular foot thereon formed for engagement with a T-slot in a machine part, a sleeve having a counterbore in the upper end thereof, mounted for rotative and vertical adjustments on said column, a screw in the upper end of said column, a flange thereon seated in said counterbore and flush with the top of said sleeve, a plate having an arcuate

slot in the face thereof mounted for pivotal movement on said column, a dowel pin in said plate engaged with said sleeve, a tool supporting block mounted for rocking movement in the arcuate slot in said plate, an overhanging boss in said sleeve having a tapped opening therein, the axis of said opening being disposed in vertical alignment with the center of said arcuate slot, and a cap screw in said boss disposed in axial alignment with the center of said arcuate slot.

PETER LUSTRIK.
